COMPRESSOR COOLING IN REFRIGERATING APPARATUS

Lawrence A. Philipp, Detroit, Mich., assignor to
Nash-Kelvinator Corporation, Detroit, Mich., a
corporation of Maryland

Application August 31, 1950, Serial No. 182,608

3 Claims. (Cl. 62—117.4)

1

This invention relates to refrigerating apparatus and more particularly to dissipating heat from said apparatus during the operation thereof.

One of the objects of my invention is to provide for a refrigerating system, a new and improved arrangement for dissipating heat from a refrigerant motor-compressor unit.

Another object of my invention is to provide for a refrigerating system installed in a refrigerator cabinet, a new and improved arrangement for dissipating heat from the refrigerant motor-compressor unit and to position such unit so that the heat dissipated as aforesaid is utilized to induce and augment the flow of air about said unit and the condenser of said system in said cabinet.

Another object of my invention is to provide for dissipating heat from a motor-compressor unit by a secondary refrigerating system which is secured to and carried entirely by the motor-compressor unit casing.

Another object of my invention is to provide for the removal of heat from a casing which houses a motor-compressor unit of a refrigerating system by placing a plurality of L-shaped secondary refrigerating systems in spaced apart relation about the casing of the motor-compressor unit so as to dissipate the heat from the motor-compressor unit into the ambient air about said unit.

Further objects and advantages of the present invention will be apparent from the following description, reference being had to the accompanying drawings, wherein a preferred form of the present invention is clearly shown.

In the drawings:

Fig. 1 is a schematic illustration of a refrigerating system embodying features of my invention;

Fig. 2 is a top view of a motor-compressor unit shown in Fig. 1 and showing my improved arrangement for dissipating the heat from said motor-compressor unit; and

Fig. 3 is a diagrammatic illustration of a cabinet with the system disclosed in Fig. 1 installed in said cabinet.

Referring to the drawings, the numeral 20 designates, in general, a refrigerating system which includes a motor-compressor unit 22, condenser 24 and evaporator 26. The motor-compressor unit 22 includes a casing 30 which houses a motor 32 and compressor 34. The motor 32 and compressor 34 are secured together by a casting 36 which is pressed into the casing 30 so that the motor and compressor are in thermal heat contacting relationship with the casing 30. The compressor 34 on the discharge side is connected to

2

condenser 24 by a conduit 40, and the condenser is connected to evaporator 26 by a small diameter or capillary tube 42. The evaporator is connected to the inlet of the compressor through a vapor return conduit 46.

During operation of the motor-compressor unit, gaseous refrigerant is withdrawn from the evaporator 26 through the vapor return conduit 46 where it enters the compressor and is compressed and discharged into conduit 40, which conducts the compressed refrigerant to the condenser 24. The refrigerant is condensed in the condenser and flows therefrom to the small diameter or capillary tube 42 which controls the flow of liquid refrigerant to the evaporator 26. This is the usual operation of refrigerating systems now in extensive use.

During operation of the motor-compressor unit there is considerable heat generated within the 20 casing due to the mechanical and frictional losses of the compressor and due to electrical losses of the electric motor 32.

In many instances it is desirable to provide means for dissipating heat from the motor-compressor unit so as to prolong the life of the motor windings and the compressor. In this connection, I have provided a plurality of secondary refrigerating systems 50 and, as shown, four of same are employed, preferably brazed to the casing 30 of the motor-compressor unit so as to provide good contact therewith. These secondary systems may be any type of tubing partially filled with liquid refrigerant, as shown at 52. Preferably, these systems are L-shaped and arranged in inverted fashion with the vertical portion 54 of the L being secured to the casing and the horizontal leg 56 extending outwardly away from the casing. Fins 58 are secured to each horizontal leg to aid in dissipating heat from the tubing. As noted in Fig. 2, the upper part of the casing is smaller than the lower part thereof and the upper part is eccentrically positioned with respect to the lower part thereof. It will be noted that the horizontal legs of the secondary system 50 extend in the direction of which the lower portion of the casing extends away from the upper portion of the casing.

During operation, when the aforesaid heat is generated within the casing and must be dissipated therethrough and therefrom, the liquid refrigerant, which is preferably volatile refrigerant, is evaporated by the heat applied thereto and the gaseous refrigerant flows into the horizontal legs of the secondary refrigerating systems where the gas is condensed in the tubing with the aid of the

heat transfer surfaces provided by the fins 58. This arrangement materially affects the cooling of the upper portion of the casing so as to prevent over-heating and reduced life of motor windings and also conducts heat away from the interior of the casing and away from the compressor unit proper.

In addition to the above characteristics of my invention, it will be noted that the secondary systems are secured to and carried by the motor-compressor unit without the aid of additional means, so that same may be readily removed with the compressor and originally shipped for installation along with the compressor.

This particular arrangement of dissipating the heat from the motor-compressor unit is also advantageous when installed in the cabinet 60 of the type disclosed in Fig. 3, which cabinet may be the same as that disclosed and described in my Patent No. 2,485,066, issued October 18, 1949. This cabinet includes a food storage compartment 62 and a sloping rear wall section 64. The sloping rear wall section 64 provides a machinery compartment 66 at the rear of said wall in which the motor-compressor unit 22 is located. At the rear of the machinery compartment 66 is placed the condenser 24, which is carried by a sheet of metal member 68, which may be like the sheet metal member disclosed in the aforesaid patent, to support the condenser and motor-compressor unit, as disclosed and described in said patent.

With the installation of the motor-compressor unit in the angularly shaped machinery compartment, it will be noted that the sloping or angular wall 64, together with the sheet metal member 68, provides an upwardly inclined flue so that air may enter the bottom opening of the machinery compartment 66 and pass over the motor-compressor unit and condenser, thereby causing the heat to flow through said flue. In accordance with the present invention, the secondary refrigerating system dissipates heat from the motor-compressor unit from various sides of the motor-compressor unit into the angularly formed machinery compartment or upwardly inclined flue, so as to create and induce the upward flow of air through the flue and over the motor-compressor unit and about the condenser.

From the foregoing it will be noted that I have provided a new and improved arrangement for dissipating heat from a motor-compressor unit. Also, it will be noted that I have utilized this characteristic for increasing the flow of heat through the flue of the cabinet in which the motor-compressor unit is installed. It will also be noted that I have provided this improved arrangement by the use of independent secondary refrigerating systems which are secured to and entirely carried by the motor-compressor unit.

Although only a preferred form of the invention has been illustrated, and that form described in detail, it will be apparent to those skilled in the art that various modifications may be made therein without departing from the spirit of the invention or from the scope of the appended claims.

I claim:

1. In refrigerating apparatus, a cabinet having a cooling compartment and a machinery com-

partment, a wall member spaced from a wall of said cabinet in overlying relationship to said machinery compartment forming therewith an upwardly tapering flue to induce flow of heat away from said machinery compartment, a refrigerant evaporator arranged to absorb heat from said cooling compartment, a refrigerant motor-compressor unit in said machinery compartment operatively connected to said evaporator, a refrigerant condenser operatively connected to the motor-compressor unit and to said evaporator, and a secondary refrigerating system having a portion in thermal heat conducting relationship with said motor-compressor unit and a portion extending outwardly therefrom into said flue and terminating therein below the apex of said tapering flue to aid in inducing the flow of air through said flue and about said condenser and motor-compressor unit.

2. In refrigerating apparatus, a cabinet having a cooling compartment and a machinery compartment, a wall member spaced from a wall of said cabinet in overlying relationship to said machinery compartment forming therewith an upwardly extending flue to induce flow of heat away from said machinery compartment, a refrigerant evaporator arranged to absorb heat from said cooling compartment, a refrigerant motor-compressor unit in said machinery compartment operatively connected to said evaporator, a refrigerant condenser operatively connected to the motor-compressor unit and to said evaporator, and a secondary refrigerating system having a portion in thermal heat conducting relationship with said motor-compressor unit and a portion extending outwardly therefrom into said flue and terminating therein below the upper extremity of said machinery compartment to aid in inducing the flow of air through said flue and about said condenser and motor-compressor unit.

3. Refrigerating apparatus comprising, a refrigerant compressor, an electric motor connected to drive said compressor, said motor and compressor generating heat, a casing enclosing said motor and compressor in heat conducting relationship and having a dome, a plurality of inverted L-shaped tubes attached to the dome in heat conducting relationship and each containing a quantity of refrigerant, said inverted L-shaped tubes each having a vertical leg in contact only with said dome and each having a horizontal leg extending a distance less than the diameter of said dome, and means sealing opposite ends of said tubes.
